DESIGN FOR A METAL SPONGE-CUP.

56,621.

Specification for Design. Patented Nov. 16, 1920.

Application filed September 18, 1919. Serial No. 324,698. Term of patent 14 years.

To all whom it may concern:

Be it known that we, HOWARD MERKEL and RAYMOND W. GUY, citizens of the United States of America, residing at West Springfield and Longmeadow, respectively, county of Hampden, and State of Massachusetts, have invented a new, original, and ornamental Design for Metal Sponge-Cups, of which the following is a specification, reference being had to the accompanying drawing, forming part thereof.

Figure 1 is a plan view of a metal sponge cup, showing our new design.

Fig. 2 is a side elevation, partly in vertical section.

We claim:

The ornamental design for a metal sponge cup as shown.

HOWARD MERKEL.
